A. H. TINNERMAN

STOVE DOOR AND FRAME CONSTRUCTION

Filed Dec. 6, 1923

FIG. 3

INVENTOR
Albert H. Tinnerman,
By Walter Macklin,
ATTORNEY

UNITED STATES PATENT OFFICE.

ALBERT H. TINNERMAN, OF CLEVELAND, OHIO.

STOVE DOOR AND FRAME CONSTRUCTION.

Application filed December 6, 1923. Serial No. 678,870.

To all whom it may concern:

Be it known that I, ALBERT H. TINNERMAN, a citizen of the United States, residing at Cleveland, in the county of Cuyahoga and State of Ohio, have invented a certain new and useful Improvement in a Stove Door and Frame Construction, of which the following is a full, clear, and exact description, reference being had to the accompanying drawings.

This invention relates to stoves and has for its general object the provision of a frame construction comprising the front of a stove such as a gas range, embodying features which are directed to prevent the destruction or damaging of enamel finish of the frame consequent to the escape of hot gases from the oven or ovens thereof when the doors are open.

It is the present custom to manufacture ranges in such manner that the panels and frame members and in fact all exposed parts of the stove may be enameled or highly polished for the sake of appearance and cleanliness. It is desirable that a white enamel finish be provided on the front portions of the stove and particularly on the doors and door frames thereof. A vitreous enamel which is more or less brittle and preferably white in color gives the most desirable finish, but the manufacture and service upkeep of stoves so finished involves many attendant difficulties after the stoves are placed in domestic service.

One of the principal difficulties encountered by manufacturers is the rapid destruction of that portion of the enamel finish which is immediately above the oven doors due to impinging hot gases upon the enameled surfaces when the oven doors are opened or when the doors are slightly ajar.

The purpose of this invention therefore is to provide an oven door and frame construction which will protect such enameled surfacing by causing the hot escaping gases to be directed away from these enameled surfaces which will insure the prevention of the escaping of hot gases from the upper portions of the oven, when the doors are slightly ajar.

A more specific object of my invention is the provision of a simple and effective means embodied in a stove frame construction in such manner as to be only an incidental detail in the manufacturing of the stove

parts whereby I obtain the desired result economically.

Other objects of my invention will herein-after be set forth in the following description which refers to the accompanying drawing illustrating a preferred embodiment thereof. The essential characteristics are summarized in the claims.

In the drawings Fig. 1 is a front elevation of a gas range embodying the features of my invention; Fig. 2 is a cross-sectional elevation taken substantially along the line 2-2 of Fig. 1; Fig. 3 is an enlarged fragmentary cross-sectional elevation taken substantially along the lines 3-3 of Fig. 1.

It is customary to form the front of a stove of a single frame member comprising either a casting or a stamped or pressed metal member which constitutes the supporting frame for both the baking oven door and broiler door in the usual type of gas ranges, the baking oven usually being arranged above the broiler. As shown in the drawings I preferably form the front of the stove by the use of a cast frame 10 which constitutes a support for the oven door 11 and lower oven or broiler door 12. These doors are attached to the front frame member 10 by suitable hinge pieces 13 which engage lugs 14 depending from the lower corners of the door frames. The door frames 11 and 12 are usually polished or nickelated and are provided with central panels 15 having an enamel finish.

It is the practice to have an enamel finish on the frame 10 which corresponds to the finish of the door panel 15 and it is this enamel on the frame 10 which is particularly subjected to damage by the hot gases escaping from the upper regions A and B of the baking oven and broiling oven respectively when the doors are open. It will be seen from the drawings that as the doors swing open the gases will escape through the upper portion of the door openings and be concentrated along the portions 10^a or 10^b of the frame 10 thus causing a checking or a discoloration of the enamel finish after the stove is used a short period in the home.

I overcome the above mentioned difficulty in a very simple manner by forming flanges or baffles on the frame 10 which extend around the upper half of the door opening edges thereof and such flanging may take any form conducive to economical manu-

facturing. As shown in the drawings the frame 10 is provided with integrally formed flange portions 20 and 21 about the margin of the baking oven and broiler door openings which extend outwardly a sufficient distance to direct the hot gases escaping from the oven regions A and B away from the enameled surfaces 10^a and 10^b of the frame. When the hot gases, as indicated by the full line arrows in Fig. 3, escape outwardly and upwardly through the oven door opening the flange 20 will be effective in leading these gases away from the finished surface 10^a and by reason of the formation of the depression 25 which is in the nature of a trough for the reception of the door edge or lip 26, a rarification of the air in this space will take place due to the rapid outward and upward movement of the hot gases, thus causing cool air to flow inwardly over the enameled surface 10^a. The provision of the flanges 20 and 21 in the manner described, it will be seen has a two-fold effect in maintaining protection for the enameled surfacing in that while guiding the hot gases away therefrom, the movement of the hot gases causes a flow of cool air over these surfaces. If desired, the lining 30 of the oven doors may be so formed around the rims thereof that a spring edge 31 may be formed, which, when the door is closed will engage the flanges 20 and 21 thus resulting in an effective sealing action when the doors are closed. If through carelessness of the user the door is not completely closed the lining edges 31 will be effective in preventing the escape of the hot gases.

A stove oven constructed in accordance with the foregoing provisions, as practice has shown, will retain the enamel finish in those regions which heretofore have shown marked discolorations and checking of the enamel.

45 I claim:

1. In a stove construction, the combination of a front frame member having exposed surfaces of enamel, said frame having an upper and a lower oven door opening formed therein, doors mounted on said frame for closing the openings and grooves and flanges formed on the frame said flanges extending outwardly from said openings, a portion of the door seating into 55 the groove and overlying the flanges when the doors are closed whereby when the doors are opened hot escaping gases from the oven may be guided away from the exposed surfaces of the frame.

60 2. In a stove construction, the combination of a frame member having an opening,

a closure member therefore, said frame having a finished surface subject to damage by contact with hot gases and means including a flange and a channeled air pocket 65 between the flange and said finished surface associated with the opening at the upper portion of the perimeter thereof for insulating hot gases escaping therethrough from such finished surfaces. 70

3. In an oven construction, a door frame, having an upper and a lower door opening formed therein, doors mounted on the frame for closing said openings, means formed about the perimeter of the door openings for guiding hot gases escaping through the doorways away from the outer exposed surfaces of the frame and means on the doors for engaging said gas guiding means when the doors are slightly ajar. 75

4. In an oven construction, a front door frame having an upper and a lower oven door opening, doors supported thereby for closing said openings, there being flanges extending outwardly from the frame around the perimeter of the openings and means associated with door linings for engaging said flanges to prevent the escape of hot gases when the doors are slightly ajar. 80

5. In a stove construction the combination of a front frame member having an oven door opening and an enameled surface extending across the top of the frame adjacent the door opening, an oven door mounted on the frame, said frame having a flange extending downwardly at an obtuse angle with the enameled surface and outwardly beyond said surface when the door is open whereby buoyant hot gases are deflected beyond the enameled surface in escaping from the oven. 90

6. In a stove construction, an oven door frame, the exposed surface adjacent the top of the door frame, adapted to be coated with enamel subject to cracking when contacting with hot gases, a groove at the edges of said surfaces and a flange extending outwardly at an angle to said surfaces, the flange forming the side wall of the groove 100 and a door having a lip portion adapted to enter the groove when the door is closed, whereby when the door is opened, vacuum caused by the withdrawal of the lip from the groove, draws comparatively cool air over the enameled surfaces, the flanges cooperating with the groove in protecting the enameled surface by deflecting the heated gases outwardly away from the surfaces. 110

In testimony whereof, I hereunto affix my 120 signature.

ALBERT H. TINNERMAN.
